SHACKLE

William Stevenson, Blundellsands, Liverpool,
England

Application July 21, 1939, Serial No. 285,781

5 Claims. (Cl. 59—86)

This invention is for improvements in or relating to shackles and is concerned with the type of shackle which is U-shaped and has holes or eyes in the ends of the jaws through which a closure pin or the like is passed, one end of the closure pin being screw-threaded to screw into a correspondingly threaded eye in the shackle so that the shackle is closed when this pin is screwed home.

10 Shackles of the aforesaid type are often used for connecting ropes and chains in marine work. One difficulty which often arises in such work is that the operator connecting up the coupling has to use both hands to bring the part which is attached to the shackle and the other part which is to be located between the shackle jaws together so that time is wasted in manipulating the pin into alignment and engagement with the eyes. Another difficulty which often arises with screw-threaded shackle pins is that the pins drop out during making and connection of a coupling and the threads become damaged.

One object of the invention is to provide a simple construction of shackle and pin which will obviate the aforesaid difficulties.

25 Accordingly the present invention provides a shackle of the type above described in which the closure pin is restrained when the shackle is open, from complete withdrawal from the shackle eyes by an abutment on the pin co-operating with a stop on the shackle. Preferably the abutment is spaced apart from its co-operating stop by an amount which permits the end of the pin to be retracted into that eye of the shackle which is remote from the end of the pin when the latter is in the closed position.

According to a further feature of the invention there is provided a shackle of the type described wherein an abutment is located on the pin so that it lies against the interior face of one jaw (when the pin is in the closed position) and wherein the interior face of the other jaw is recessed towards its exterior face, the base of the said recess forming a stop for the abutment, whereby the abutment may be accommodated in the said recess when the shackle is opened. Conveniently the abutment is spaced from the base of the recess by a distance which is substantially equal to the distance between the head of the pin and the start of the thread remote from such head.

50 In the accompanying drawing which shows various forms of the invention by way of example:

Figure 1 is a part-sectional elevation of a shackle with the closure pin in the closed position;

Figure 2 is a sectional elevation on the line II—II of Figure 1;

Figure 3 is a fragmentary detailed sectional elevation to an enlarged scale of the shackle pin

adjacent the threaded end of the shank and showing one method of constructing an abutment;

Figure 4 is a sectional elevation on the line IV—IV of Figure 3;

Figure 5 is a view similar to Figure 3 but showing an alternative method of forming the abutment;

Figure 6 is a sectional elevation on the line VI—VI of Figure 5;

Figure 7 is a similar view to Figure 3 showing a further alternative construction of the abutment;

Figure 8 is a sectional elevation on the line VIII—VIII of Figure 7;

Figure 9 is a part-sectional elevation of a shackle having one threaded eyelet hole and a correspondingly threaded pin;

Figure 10 is a fragmentary detailed sectional view of a modified form of abutment on the pin;

Figure 11 is a part-sectional view of the ends of the shackle jaws with a modified form of pin closing the jaws.

Figure 12 is a part-sectional view of a modified spring abutment.

The shackle shown in Figures 1 and 2 is of the common inverted U-form, the jaws 10 of which have eyes 11 and 12 formed in the ends thereof and in alignment to receive a closure pin 13.

The eyes 11 and 12 are of different internal diameters, and are screw-threaded respectively at 14 and 15.

The closure pin 13 has one end 16 screw-threaded to engage with the eye 11, and the other end 17 of larger diameter than the end 16 and screw-threaded to engage with the corresponding threads 15 of the eye 12. The end of the pin has a turning head 18 for screwing the pin home in the closed position. This type of shackle and pin has the material advantage that by reason of the threaded engagement of the pin with both the shackle eyes, the pin serves as a strut or a tie to prevent collapse or distention of the shackle jaws. Since, however, the pin has two sets of threads on it it is important to avoid damage to these threads by the dropping of the pin.

In order to prevent complete disengagement of the pin 13 from the jaws 10 an abutment 19 is provided on the pin adjacent the threaded portion 16 thereof, and this abutment lies against the inside face of one shackle jaw when the pin is screwed home as shown in Figure 1. The jaw 10 having the eye 12 is slotted at 20 on its interior face to receive the abutment 19 when the shackle pin is retracted from the closing position, but the slot 20 is not carried through to the outer face of the jaw so that a stop 21 is formed by the base of the slot against which the abutment 19 rests as the pin is withdrawn so

that the shackle pin cannot be disengaged from the shackle. Since, however, the jaws of the shackle must be left clear for the insertion of the part to which the shackle has to be connected the abutment 19 must be as thin as possible providing that it has the necessary strength to hold the weight of the shackle in the retracted position. Similarly the slot 28 is carried through the shackle arm sufficiently far so that the stop 21 is only strong enough to hold the shackle pin in the retracted position. From this it will be seen, as shown in chain-dotted lines in Figure 1, that when the shackle pin is retracted to open the jaws an almost negligible projection of the end of the pin is present due to the combined thicknesses of the abutment 19 and the stop 21. The degree of projection of the end of the pin is dependent on the spacing of the abutment on the pin and the stop on the shackle (considered axially of the pin) being as nearly equal as possible to the distance between the turning head of the pin and the start of the thread remote from such turning head. The width of the abutment 19 and of the corresponding slot 28 (see Figure 2) is maintained at a minimum consistent with the abutment and stop having sufficient strength to carry the weight of the pin, and by this arrangement a full bearing surface between the pin and the shackle eyes is obtained.

It will be observed that the construction described does not weaken the shackle to any extent but yields the very material advantage that the shackle pin when withdrawn to open the jaws cannot become disengaged from the eye-holes and fall out and the threads become damaged when, for example, working at heights above the deck of a ship; similarly if the operator has to hold the shackle attached to one part and another part to be located between the jaws of the shackle, on turning the shackle round the pin will slide towards the closed position by gravity enabling the manipulator to effect a coupling.

In Figures 3 and 4 the abutment 19 is formed by channelling the shank of the pin 13 adjacent the threads 16 with a morticing tool and turning the metal which has been channelled upwardly to form the abutment.

In Figures 5 and 6 the abutment is formed by means of a small angle iron countersunk at 22 in the shank 13 and spot-welded in position.

In Figures 7 and 8 the abutment is formed by tapping a hole 23 in the shank 13 and inserting a grub screw 24 with a flattened projecting part 25.

The modification shown in Figure 9 is applied to the common type of shackle having a closure pin with one threaded end 16 engaging a correspondingly threaded eye 11, the shank 26 of the pin 13 being plain up to the turning head 27. The abutment 19 engages the stop 28 at the end of a slot 29 in the shackle jaw 30.

In the detailed view comprising Figure 10 the abutment 19 is hinged at 31 to a base plate 32 countersunk and spot-welded in a recess 33 in the pin 13. A spring 34 biases the abutment 19 to its upright position. This construction of pin and abutment is used in conjunction with the shackle having slotted jaws shown in Figure 1. In some classes of work in which shackles are used the shackle pin has to be threaded through a loop in, for example, the end of a rope to be attached to the pin, and this loop may be substantially equal to the diameter of the pin; thus to pass the pin through the loop the abutment

must be capable of folding down against its spring 34.

In Figure 11 the threaded end 16 of the pin 13 incorporates one or more spring-pressed plungers 35 only one of which is shown in Figure 5 10. This spring-pressed plunger when released from the eye-hole 11 of the shackle jaw 10 forms an abutment which will engage in the recess 36 on the inside surface of the eye-hole 12, thereby enabling the whole of the threaded end 16 to be 10 housed within the eye-hole 12, and leaving the space between the jaws 10 entirely unobstructed.

In the modification illustrated in Figure 11 the retaining means of the shackle pin is not so positive as the retaining means illustrated in Figures 1 to 10, but the construction may be used where it is essential to have the jaws entirely unobstructed.

In the modification illustrated in Figure 12 the abutment 19 comprises a leaf spring bent 20 to form a retaining pawl, the tail of the spring 37 being spot-welded in the recess adjacent the threads 16.

I claim:

1. A shackle comprising a U-shaped body part, 25 the jaws of which have eye-holes, at least one of which is internally threaded, a closure pin having a turning head and a screw-threaded end remote from the said head, an abutment located on the pin so that it lies against the interior face 30 of one jaw when the pin is in the closed position and a recess on the interior face of the other jaw the base of which recess is adjacent the exterior face of the said jaw and forms a stop for the abutment.

2. A shackle as claimed in claim 1, wherein the base of the recess is spaced from the abutment by a distance, along the axis of the pin, which is substantially equal to the distance between the head of the pin and the start of the 40 thread remote from said head.

3. A shackle comprising a bow-shaped body part the arms of which have eye-holes in alignment with one another, and at least one of the said eye-holes being internally threaded, a closure pin having a turning head and a screw-threaded portion at the end of the pin remote from the said head, a spring-pressed abutment on the pin adjacent the threaded end thereof, and a corresponding recess in the eye-hole adjacent the turning head, when the pin is in the closed position, which recess receives the said spring-pressed abutment on withdrawal of the pin to restrain the pin from complete separation with the shackle body part.

4. A shackle as claimed in claim 1 and having an abutment-receiving recess open to one eye-hole, and a spring-pressed abutment on the pin adapted to engage in the said recess and hold the end of the pin within the eye-hole when the pin is withdrawn to open the shackle.

5. A shackle comprising a U-shaped body part the jaws of which have eye-holes at least one of which is internally threaded, a closure pin having a turning head, and a screw-threaded end remote from the said head, an abutment located adjacent the screw-threaded end of the pin and angularly movable towards and away from the axis of the pin, a yielding device between the abutment and the pin and biasing the abutment to its projecting position, and a stop for the said abutment on the shackle whereby the pin when the shackle is opened is restrained from complete withdrawal.
